PORTABLE OARLOCK

Samuel A. Black, Chicago, Ill.

Application December 4, 1946, Serial No. 713,962

9 Claims. (Cl. 9—26)

1
The present invention relates to oarlock or rowlock structures and more particularly to a portable type of device.

Among the objects of the invention is to provide a novel oarlock or rowlock support structure which is readily selectively attached at any given point or locus of the gunwale of a boat, such as fishing boats or the like, to afford convenient operation of the oar or oars at any chosen part of the boat and comprises relatively adjustable clamp parts or members adapted to be fitted to any selected portion of the gunwale, together with tightening elements for causing the clamp parts to be firmly attached to the gunwale, one of the clamp parts having rigid therewith the oarlock or rowlock socket which pivotally carries the oar saddle or strap.

Another object of the invention is to provide means for the clamp parts to be adjustable for clamping the gunwale both in width and height and adaptable to different sizes and shapes of gunwales, while using a single means of tightening the clamp parts for the coordinate clamping in both ways of gunwales.

Other objects, capabilities, advantages, features, and the like are comprehended by the invention as will later appear, and as are inherently possessed by the invention.

Referring briefly to the drawings:

Fig. 1 is a perspective view of an embodiment constructed in accordance with the invention;

Fig. 2 is a top plan view thereof with a part of the gunwale of the boat;

Fig. 3 is a transverse sectional view thereof taken in a plane represented by line 3—3 in Fig. 2 of the drawings; and,

Fig. 4 is a side view of the device.

Referring more in detail to the drawings, the embodiment chosen to illustrate the invention is shown as comprising an oarlock thole or socket 1 serving as a fulcrum for the oar saddle or strap having a pin or pintle (not shown) rotative in the socket 1. Rigid or integral with the socket 1 is a clamp member or part 2 of angle form comprising a plate part 3 adapted to overlie the gunwale of the boat, a flange part 4 adapted to abut the outer side of the gunwale and being preferably formed integral with the socket 1. The plate part 3 has one or more slots 5 for the passage therethrough of clamping bolts 6 or other suitable securing elements.

The device is adapted for attachment to the gunwale of a boat comprising a gunwale runner 7 extending along the upper side portion 8 of the side 9 of the boat. Within the side 9 of the boat

2
are fixed upstanding bracing ribs 10 which are curved to follow the curvature of the body or hull of the boat, as shown in Fig. 3. To the upper end parts of these ribs 10 is fixed an inner gunwale part or brace runner 11 providing spaces 10a between the runners 7 and 11 and between the ribs.

Upon the plate 3 is placed another clamp member or part 12 on the inner side of the gunwale and having a plate part 13 provided with one or more slots 14 in registry with slots 5 of the plate part 3 and for the passage therethrough of the bolts 6. The clamp member 12 also comprises a flange part 15 to be disposed laterally within the gunwale part 11, as shown in particular in Fig. 3.

Beneath the gunwale part or runner 11 is placed a third clamp member 16 having a lower plate 17 provided with one or more slots 18 in alignment with the slots 5 and 14 and for the passage of the bolts 6, the plate part 17 being adapted to be clamped to the underside of the gunwale part or runner 11, as shown in Fig. 3. The clamp member 16 also has upstanding flange parts or portions 19 and 20 of which the flange part 20 is interposed between the flange 15 of the upper clamp 12 and the gunwale runner 11 to be clamped therebetween, and the flanges 19 are disposed outwardly of the flange 15 (see Fig. 3) to be clamped thereagainst. The lower clamp member 16 is relatively adjustable to the clamp member 12 depending upon the vertical dimension of the gunwale runner 11, so that when the device is attached to the gunwale of the boat, the clamp member 16 will be clamped upwardly against the gunwale runner 11 while at the same time the upper clamp members 2 and 12 are clamped to the upper part of the gunwale generally.

The bolts 6 extend upwardly through the slots 18, 5 and 14 and are provided with heads 21 to abut the lower side of the plate part 17 against the underside of the runner 11 and with threaded upper ends 22 to which may be threadedly engaged nuts, such as thumb nuts 23, for drawing on the bolts 6 and to clamp the clamp members 2 and 12 together and to the upper part of the gunwale generally, as well as clamp the clamp member 16 to the underside of the gunwale rail or runner 11.

The length of the slots 5, 14 and 18 are such as to adapt the device to different widths of gunwales with which the boats may be provided.

When it is desirable to operate the oars at any part of a boat as may be desired, as for example, near the aft of the boat, the devices may be de-

tached from the places where they were previously used by loosening and disconnecting the bolts 6 and then locating the clamp members 2, 12 and 16 at the selected locus, the bolts inserted in place, the clamp members 2 and 12 as also the clamp member 16 pressed toward the gunwale generally into lateral abutments and then the bolts 6 tightened by screwing down the thumb nuts 23. The device generally will be held firmly in place without any danger of the clamp members skewing or cocking. The flanges 19 and 20 are so placed and extend along the flange 15 sufficiently to give a stable purchase between the clamp members 12 and 16 to prevent any relative tipping or cocking when the bolts 6 are tightened.

While I have herein described and upon the drawings shown an illustrative embodiment of the invention, it is to be understood that the invention is not limited thereto but comprehends other constructions, arrangement of parts, details, features and the like, without departing from the spirit of the invention.

Having thus disclosed the invention,

I claim:

1. A portable oarlock structure comprising a pair of relatively adjustable clamping members having portions for clamping the sides of a gunwale of a boat and having slots adapted to be in registry with each other when adjusting the relation of said members, one of said members carrying an oarlock socket, a third clamping member having a portion relatively adjustable with respect to one of said first mentioned members, said third member having a slot adapted to be in registry with the slots of said first mentioned members, and a tie element extending through said slots for clamping said members to the gunwale of the boat.

2. A portable oarlock structure comprising a pair of relatively adjustable clamping members having body portions for overlying a gunwale of a boat and having laterally extending portions for clamping the sides of the gunwale of the boat, said body portions having slots adapted to be in registry with each other when adjusting the relation of said members, one of said members carrying an oarlock socket, a third clamping member having a portion relatively adjustable with respect to one of said first mentioned members, said third member having a slot adapted to be in registry with the slots of said first mentioned members, and a tie element extending through said slots for clamping said members to the gunwale of the boat.

3. A portable oarlock structure comprising a pair of relatively adjustable clamping members having body portions for overlying a gunwale of a boat and having laterally extending portions for clamping the sides of the gunwale of the boat, said body portions having slots adapted to be in registry with each other when adjusting the relation of said members, one of said members carrying an oarlock socket, a third clamping member having a body portion for underlying the gunwale of the boat and having a laterally extending portion which is relatively adjustable with respect to a laterally extending portion of one of said first mentioned members, and a tie element extending through said slots for clamping said members to the gunwale of the boat.

4. A portable oarlock structure comprising a pair of relatively adjustable clamping members having body portions for overlying a gunwale of a boat and having laterally extending portions for clamping the sides of the gunwale of the boat,

said body portions having slots adapted to be in registry with each other when adjusting the relation of said members, one of said members carrying an oarlock socket, a third clamping member having a body portion for underlying the gunwale of the boat and having a laterally extending portion which is relatively adjustable with respect to a laterally extending portion of one of said first mentioned clamping members, said third member having a slot adapted to be in registry with the slots of said first mentioned members, and a tie element extending through said slots for clamping said members to the gunwale of the boat, said laterally extending portion of said third member comprising spaced parts for slideably abutting the opposite faces of said last mentioned laterally extending portion of one of said first mentioned clamping members.

5. A portable oarlock structure comprising a pair of relatively adjustable angle shaped clamping members of which a leg of each of said members overlies the gunwale of a boat and of which the other legs of said members abut the opposite sides of the gunwale, said first mentioned legs having slots adapted to be in registry with each other when adjusting the relation of said members, one of said members carrying an oarlock socket, a third clamping member having a portion relatively adjustable with respect to one of said first mentioned members, said third member having a slot adapted to be in registry with the slots of said first mentioned members, and a tie element extending through said slots for clamping said members to the gunwale of the boat.

6. A portable oarlock structure comprising a pair of relatively adjustable angle shaped clamping members of which a leg of each of said members overlies the gunwale of a boat and of which the other legs of said members abut the opposite sides of the gunwale, said first mentioned legs having slots adapted to be in registry with each other when adjusting the relation of said members, one of said members carrying an oarlock socket, a third angle shaped clamping member of which a leg thereof underlies the gunwale of the boat and of which the other leg thereof has relatively adjustable contact with a leg of one of said first mentioned members, said third member having a slot adapted to be in registry with the slots of said first mentioned members, and a tie element extending through said slots for clamping said members to the gunwale of the boat.

7. A portable oarlock structure comprising a pair of relatively adjustable angle shaped clamping members of which a leg of each of said members overlies the gunwale of a boat and of which the other legs of said members abut the opposite sides of the gunwale, said first mentioned legs having slots adapted to be in registry with each other when adjusting the relation of said members, one of said members carrying an oarlock socket, a third angle shaped clamping member of which a leg thereof underlies the gunwale of the boat and of which the other leg thereof has relatively adjustable contact with a leg of one of said first mentioned members, said third member having a slot adapted to be in registry with the slots of said first mentioned members, and a tie element extending through said slots for clamping said members to the gunwale of the boat, said other leg of said third member comprising spaced parts for slideably abutting the opposite faces of one of said other legs of one of said first mentioned members.

8. A portable oarlock structure comprising a plurality of relatively adjustable clamping members of which a first of said members has a body portion to overlie the gunwale of a boat and has a flange portion for abutting a side of the gunwale, and of which a second of said members has a body portion to overlie the gunwale of the boat and has a flange portion for abutting the opposite side of the gunwale, and of which a third of said members has a body portion to underlie the gunwale and has a flange portion for abutting the flange portion of said second member, said body portions having slots, and a tie element extending through said slots for clamping said members to the gunwale, said first member carrying an oarlock socket.

9. A portable oarlock structure comprising a plurality of relatively adjustable clamping members of which a first of said members has a body portion to overlie the gunwale of a boat and has a flange portion for abutting a side of the gunwale, and of which a second of said members has a body portion to overlie the gunwale of the boat

5
